ISAAC H. MILLIKEN, OF ASPINWALL, PENNSYLVANIA, ASSIGNOR TO THE McCONWAY & TORLEY COMPANY, OF PITTSBURGH, PENNSYLVANIA, A CORPORATION OF PENNSYLVANIA.

DRAFT-RIGGING.

1,333,271.

Specification of Letters Patent.

Patented Mar. 9, 1920.

Application filed July 17, 1917. Serial No. 181,090.

To all whom it may concern:

Be it known that I, ISAAC H. MILLIKEN, a citizen of the United States, residing at Aspinwall, in the county of Allegheny and State of Pennsylvania, have invented certain new and useful Improvements in Draft-Rigging; and I do hereby declare the following to be a full, clear, and exact description of the invention, such as will enable others skilled in the art to which it appertains to make and use the same.

My invention relates to draft rigging for railway cars, and its primary object is to provide simple, strong, durable and efficient means for pivotally connecting the coupler to a draft yoke having a hooded forward end. In a broad aspect the invention involves the combination of a coupler and draft yoke so formed as to be capable of being brought into assembled and interlocked relation through a relative rotation of the parts about a transversely extending axis passing between the arms of the yoke. There are also other features of invention involving special details of construction of the elemental parts as well as particular combinations, all as will hereinafter more fully appear and be pointed out in the claims.

In the drawings illustrating the best mode in which I contemplate applying the principle of the invention,

Figure 1 is a plan view of a coupler and draft yoke, a portion of the stem of the coupler being omitted.

Fig. 2 is a side elevation of the device shown in Fig. 1, the forward portion of the coupler being omitted.

Fig. 3 is a detail plan view of the rear end of the coupler.

Fig. 4 is a vertical longitudinal section of the assembled construction shown in Figs. 1 and 2.

Fig. 5 is a detail sectional view, taken on the line 5—5, Fig. 2.

Fig. 6 is a detail view, partly in side elevation and partly in section, illustrating the manner of assembling and disassembling the parts.

In the drawings, 1 indicates the coupler and 2 is the draft yoke. The coupler may be, and preferably is, supported near its outer end by a carry-iron 3 of the well-known type that is rigidly secured to the underframe of the car. The draft yoke 2 is adapted to receive between its arms 4 and 5 suitable

springs and followers or other shock cushioning mechanism or units (not shown) and to cooperate therewith in the usual way. The draft yoke is preferably of the hooded type, the forward ends of its arms 4 and 5 being rigidly connected at the outer sides by inclined tie bars or braces 6 which prevent separation or spreading of the forward ends of the yoke arms.

The coupler 1 and draft yoke 2 are interlockingly connected by means of interengaging lugs or shoulders, which are preferably so fashioned as to enable the coupler to have a pivotal or swinging movement with respect to the yoke. To this end, the longer arm 4 of the yoke is provided at its forward end with an inwardly extending lug or shoulder 7 whose curved face or pivotal bearing is preferably undercut and of segmental concave form, as indicated at 8; while the shorter arm 5 of the yoke is similarly provided with an inwardly extending lug or shoulder 9 whose rear bearing face is likewise undercut or beveled, but which is convexly curved, as at 10, the curved bearing surfaces 8 and 10 having the same pivotal axis or axis of curvature and being upon opposite sides of such axis. The forward face 11 of the yoke lug 7 is preferably curved concentrically with the rear bearing face 8, thereby adapting it for cooperation with an upwardly extending similarly curved lug 12 on the coupler to thus prevent rearward movement of the coupler 1 with respect to the draft yoke. The upper surface of the lug 9 is beveled or inclined downwardly and forwardly, as at 13, to permit the coupler 1 to be inserted between the arms of the yoke while the parts are angularly disposed with respect to normal, as will be readily understood upon reference to Fig. 6 of the drawings.

At its rear end the coupler is provided with a plurality of lugs or shoulders 14 and 15 whose respective forward faces 16 and 17 are concentrically curved and so spaced that they are adapted to engage the similarly curved bearing faces 8 and 10 of the corresponding lugs 7 and 9 of the yoke. The inwardly projecting lugs 7 and 9 upon the draft yoke, together with the outwardly projecting lugs 14 and 15 upon the coupler form an interlocking pivotal connection between the coupler and yoke when the parts are in assembled position. Dissociation of

the elements is normally prevented by the carry-iron 3 which must be removed before the coupler 1 may be turned to an angle permitting it to be disengaged from the yoke.

5 The upper surface of the coupler to the rear of the curved pivotal shoulder 16 is curved or beveled as indicated at 18, thus permitting the coupler to be swung vertically or rotated about a transversely extending 10 axis when being assembled or disassembled. In order to provide a suitable bearing surface 19 on the rear end of the coupler for engaging the forward follower (not shown), the curved or beveled portion 18 of the 15 coupler is terminated somewhat above the longitudinal median line of the coupler and yoke, thus enabling a portion of the bearing surface 19 to extend above said median line.

What I claim is:

20 1. In a draft rigging, the combination with a draft yoke, of a coupler pivotally connected thereto so as to swing on a vertical axis, said yoke and coupler being adapted to be connected by a relative rotation of said parts about a transversely extending axis 25 passing between the arms of said yoke.

2. In a draft rigging, the combination with a draft yoke, of a coupler having interlocking engagement with said yoke, means 30 carried by the coupler for preventing rearward movement of the coupler with respect to the yoke, and means rigid with the car underframe and directly engaging the said coupler for maintaining the yoke and coupler in interlocked relation.

3. In a draft rigging, the combination with a draft yoke having inwardly extending shoulders formed on the forward ends of its arms, of a coupler having shoulders 40 adapted to coöperate with the said shoulder on the yoke, said coupler and yoke being detachable by a rotation of one of said elements about a transversely extending axis passing between the arms of said yoke.

45 4. In a draft rigging, the combination with a draft yoke, of a coupler pivotally connected thereto, said coupler being adapted to be inserted between the arms of said yoke at an angle thereto and to be brought to assembled position by a movement in a plane at right angles to the planes of the arms of said yoke.

5. In a draft rigging, the combination with a draft yoke having arms of unequal 55 length and a plurality of shoulders, of a coupler having a correspondingly shouldered end adapted to coöperate with the shoulders on the yoke, the said shoulders of the yoke arms being out of alignment transversely of the yoke.

6. In a draft rigging, the combination with a draft yoke provided with inwardly extending shoulders on the adjacent faces of its arms, said shoulders being out of 60 transverse alignment, of a coupler provided

with correspondingly spaced shoulders, said shoulders on the yoke and coupler constituting means for pivotally connecting said yoke and coupler.

7. In a draft rigging, the combination 70 with a draft yoke provided at its forward end with inwardly extending longitudinally spaced lugs or shoulders the inner faces of which are curved; of a coupler provided with vertically extending shoulders, the said shoulders on the yoke and coupler constituting means for pivotally connecting the one to the other, the pivotal axis of said coupler being located intermediate the said shoulders on the yoke arms. 75

8. In a draft rigging, the combination with a draft yoke provided with a hooded forward end and having an inwardly extending shoulder on each arm of the yoke adjacent its forward end, of a coupler pivotally connected to said yoke, said coupler having outwardly extending shoulders formed on its upper and lower faces, said shoulders on the coupler being adapted to pass between the shoulders on the yoke, the 80 said sets of shoulders being adapted to engage and form the pivotal connection between the yoke and coupler.

9. In a draft rigging, the combination with a hooded draft yoke having at the forward end of one of its arms an inwardly extending lug whose front and rear faces are concentrically curved, and having also at the forward end of its other arm an inwardly extending lug whose rear face is concentric 95 with the curved faces of the first mentioned lug, of a coupler having shoulders whose forward faces are adapted to respectively co-operate with the rear faces of the said yoke lugs to thereby form a pivotal connection between said yoke and coupler, and means on the said coupler engaging the forward curved face of one of the yoke lugs to prevent rearward movement of the coupler independently of the said yoke. 100

10. A draft yoke having arms of unequal length, each of said arms being formed at its free end with an inwardly extending shoulder adapted to extend in front of a corresponding shoulder of a coupler, said shoulders on the yoke being out of transverse alignment. 115

11. A draft yoke having inwardly extending lugs whose rear faces form concentrically curved segmental pivotal bearings arranged on opposite sides of their axis of curvature. 120

12. A draft yoke having the forward ends of its arms connected by bars whose forward edges extend obliquely to the arms of said yoke, said arms being provided with inwardly extending longitudinally spaced lugs adapted to engage the forward faces of correspondingly spaced lugs on a car coupler. 125

13. A coupler having concentrically curved 130

segmental pivots arranged on opposite sides of their axis of curvature.

14. A coupler having at its rear end a bearing surface adapted to engage a follower, said bearing surface being of less extent than the rear end of said coupler and being of unequal extent on opposite sides of the longitudinal median line of the rear end of the coupler stem.

15. In a draft rigging, the combination of 10 a coupler and yoke each provided with a plurality of rigidly attached members adapted to be interlockingly connected by a relative rotation, and means rigid with the car underframe for preventing the relative rotation of said members. 15

In testimony whereof I affix my signature.
ISAAC H. MILLIKEN.
